RAILWAY SIGNALING

Earl M. Allen, Swissvale, Pa., assignor to The
Union Switch & Signal Company, Swiss-
vale, Pa., a corporation of Pennsylvania

Application February 15, 1936, Serial No. 64,129

20 Claims. (Cl. 246—50)

My invention relates to railway signaling, and particularly to signaling involving wayside signals located along a trackway for governing the passage of trains.

5 A feature of my invention is the provision of novel and improved apparatus for establishing a distinctive control for each of five sections in the rear of an occupied section. Each distinctive control is effective to cause a corresponding 10 aspect of the associated wayside signal, whereby there is produced a five-block, six-indication, system of signaling.

Another feature of my invention is the provision of novel and improved apparatus for controlling the signals in such a manner that when one signal is displaying a restrictive indication, the signal for the section next in rear will display the same indication and will display a less restrictive indication only if a train consumes a 15 predetermined amount of time in approaching such signal for the section next in rear.

I will describe several forms of apparatus embodying my invention, and will then point out the novel features thereof in claims.

20 In the accompanying drawings, Figs. 1A and 1B are diagrammatic views which, when placed end to end in the order named, illustrate one form of apparatus embodying my invention. Figs. 2 and 3 are diagrammatic views illustrating modifications of a portion of the apparatus shown in Fig. 1B and each also embodying my invention.

Similar reference characters refer to similar parts in each of the several views.

25 Referring first to Figs. 1A and 1B, the reference characters 10 and 11 designate the rails of a stretch of railway track along which traffic normally moves in the direction indicated by the arrows. These rails are divided by insulated joints 12 into a plurality of track sections 3T, 4T, 5T, 6T, 7T, 8T, etc. Each section is provided with a track circuit which includes a track battery 13 connected across the rails at one end of the section and a track relay, designated by the reference character R with a prefix the same as the reference character of the associated section, connected across the rails at the other end of the section.

To govern the passage of trains through the stretch of railway, a wayside signal, designated 30 by a reference character the same as the numerical prefix in the reference character of the associated section, is provided for each track section.

Each of these signals comprises an upper unit U and a lower unit L. These units may take any 35 one of several forms of signal mechanisms such

as searchlight, semaphore, color light, or position light. As here shown, each upper unit is a searchlight signal mechanism capable of displaying a red light, a yellow light, or a green light, and each lower unit L is a lamp, designated by the reference character LE with a prefix the same as the reference character of the associated signal. The lamps LE, as here shown, display a white light but may be arranged to display a colored light if desired.

5 The searchlight signals may be such as described and claimed in United States Letters Patent No. 1,864,224, issued June 21, 1932, to W. B. Wells, for Light signals. For the purpose of this application, it is deemed sufficient to but briefly 10 describe these signals. Referring to signal 3, for example, it includes a pivotally mounted rotor 14A controlled by a permanent magnet (not shown) and by an operating winding 14. Energization of the operating winding 14 with current 15 of one polarity causes the rotor 14A to be rotated in one direction moving the signal to the clear indication position; energization of the operating winding 14 with current of the reverse polarity causes the rotor 14A to be rotated in the opposite 20 direction to move the signal to the caution indication position; while deenergization of the operating winding 14 permits the rotor 14A to be returned by gravity to a center position which is the stop indication position. Associated with the 25 rotor 14A is a signal lamp 3UE. As pointed out in detail in the aforementioned patent, when the rotor 14A is rotated to the clear position, a green colored filter G is moved in front of the lamp 3UE so that a green signal light will be displayed when 30 lamp 3UE is lighted. When the rotor 14A is rotated to the caution position, a yellow colored filter Y is moved in front of lamp 3UE so that, with lamp 3UE lighted, a yellow signal light will 35 be displayed. In like manner, the positioning of the rotor 14A in the center position moves a red colored filter R in front of lamp 3UE so that a red signal light is displayed whenever lamp 3UE is energized. The rotor 14A actuates a set of circuit controlling contacts in such a manner that 40 the contact 15—16 is closed only in the clear indication position, contact 17—18 is closed only in the caution indication position, and contact 45 15—19 is closed both in the stop and caution indication positions. The lamp 3UE may be constantly burning, as shown herein, or may be approach lighted in any usual and well-known manner.

45 Each upper and lower unit of the wayside signals functions in a manner similar to that de- 50 55

scribed for the upper and lower units of signal 3.

From the foregoing description of the signals shown herein, it will be apparent that six distinctive indications may be displayed by various combinations of the upper and lower units of each signal. That is, the upper unit alone may provide three indications and the lower unit when displayed simultaneously with the upper unit may provide three additional and different 10 indications. As will be pointed out more in detail hereinafter, when an upper unit is displaying a particular indication, the lighting of the lower unit will cause that signal to display a less restrictive indication. With this arrangement, it 15 will be obvious that in the event the lamp in the lower unit should become burned out, the signal will automatically display a more restrictive indication. My system, therefore, requires no 20 light-out relays or other apparatus to prevent the display of a less restrictive indication in the event a lamp of the lower unit should become burned out or otherwise fail to light at the proper time.

Each signal is provided with a signal control 25 relay designated by the reference character LR with a prefix the same as the reference character of the associated signal. The signal control relays LR control the lower unit of the associated signal. For example, the lamp 3LE is controlled 30 over a front contact 20 of the signal control relay 3LR so that lamp 3LE is lighted whenever relay 3LR is energized.

Each signal is provided with a clear indication 35 repeating relay which is designated by the reference character DP with a prefix the same as the reference character of the associated signal and which is energized only when the upper unit of the associated signal is in its clear indication position. For example, the relay 3DP is controlled 40 over clear contact 15-16 of the upper unit of signal 3 so that relay 3DP is energized only when the upper unit U of signal 3 is in its clear position.

Each signal is provided with a pole changing 45 relay having a slow release characteristic and which is designated by the reference character HDP with a prefix the same as the reference character of the associated signal. Each pole changing relay is energized when the associated 50 repeating relay DP is energized, or when the associated upper unit is in its caution condition provided the associated signal control relay LR is then energized. For example, the relay 3HDP may be energized over a circuit which includes 55 front contact 21 of the relay 3DP or over another circuit which includes caution contact 17-18 of the upper unit of signal 3 and front contact 22 of signal control relay 3LR.

The operating winding 14 of each searchlight 60 mechanism is connected to a signal line circuit governed by the pole changing relay HDP of the signal for the section next in advance and including a front contact of the track relay for the associated section as well as a front contact of 65 the track relay for such advance section. That is, operating windings 14 of the upper mechanisms may be energized by current of one polarity or the other polarity depending upon the condition of the pole changing relay of the signal for 70 the section next in advance providing the associated section and the section next in advance are both unoccupied.

Each signal control relay LR is connected to an auxiliary line circuit one wire of which is also 75 one wire of the signal line circuit for the upper

unit of the signal with which such signal control relay is associated. The line circuit for each signal control relay LR includes a front contact of the track relay for the associated section and may be supplied by energy over a back contact of the signal control relay LR of the signal for the section next in advance, or may be supplied by energy over a front contact of the signal control relay LR for the signal in advance provided the clear repeating relay DP for such advance signal is then energized. That is, each relay LR may be energized when the associated section is unoccupied either when the signal control relay LR for the signal next in advance is deenergized, or when the signal control relay LR for the signal next in advance is energized provided the upper unit U of such advance signal is then in its clear condition.

The polarity of the auxiliary line circuit for each signal control relay LR is controlled by the pole changing relay HDP for the signal in advance in such a manner that the polarity of the two line wires is always of the proper polarity. That is, the polarity of the current supplied to the line conductors at the auxiliary line circuit is so controlled that the common line conductor is always of a polarity opposite to the polarity of the other line conductor when such other conductor is energized.

Each of the signals herein shown is controlled by the associated signal control relays LR and operating windings 14 in the following manner: When the operating winding 14 and the signal control relay LR are both deenergized (see signal 3) the upper unit U of that signal will display a red light and the lower unit L will be extinguished. Signal 3, therefore, displays a single red light to indicate "stop". When the operating winding 14 is deenergized and the relay LR is energized (see signal 4), the upper unit U of that signal will display a red light and the lower unit L will display a white light. Signal 4, therefore, will display a red light over a white light to indicate "prepare to stop at next signal". When operating winding 14 is energized in the reverse direction and the relay LR is deenergized (see signal 5), the upper unit of that signal will display a yellow light and the lower unit will be extinguished. Signal 5, therefore, will display a single yellow light to indicate "approach next signal at slow speed". When the operating winding 14 is energized in the reverse direction and the relay LR is energized (see signal 6), the upper unit of that signal will display a yellow light and the lower unit will display a white light. Signal 6, therefore, displays a yellow light above a white light to indicate "proceed at medium speed". When the operating winding 14 is energized in the normal direction and relay LR is deenergized (see signal 7), the upper unit of that signal will display a green light and the lower unit will be extinguished. Signal 7, therefore, will display a single green light to indicate "approach next signal at medium speed". When the operating winding 14 is energized in the normal direction and the relay LR is energized (see signal 8), the upper unit of that signal will display a green light and the lower unit will display a white light. Signal 8, therefore, will display a green light above a white light to indicate "proceed at normal speed".

As shown in the drawings, the section 3T is occupied by a train K so that operating winding 14 of the upper unit of signal 3 and signal control relay 3LR are both deenergized, with the result

that signal 3 displays a single red light to indicate "stop".

When signal 3 is displaying the stop indication, signal control relay 4LR is energized over a line circuit which passes from terminal B of a suitable source of energy, at signal 3, through back point of contact 23 of relay 3HDP, relay 4LR, front contact 24 of track relay 4TR, back point of contact 25 of relay, and back point of contact 26 of relay 3HDP to terminal C of the same source of energy. Lamp 4LE, therefore, is energized over front contact 27 of relay 4LR to cause signal 4 to display a red light over a white light.

15 When signal 4 is in this condition operating winding 14 of the upper unit of signal 5 is energized in the reverse direction by a line circuit which passes from terminal B at signal 4, through back point 28 of relay 4HDP, operating winding 20 14 of signal 5, front contact 29 of track relay 5TR, front contact 30 of track relay 4TR, and back point of contact 31 of relay 4HDP to terminal C. Signal 5, therefore displays a single yellow light.

25 When signal 5 is displaying this indication, operating winding 14 of the upper unit of signal 6 is energized in the reverse direction over a line circuit which passes from terminal B at signal 5, through back point of contact 32 of relay 5HDP, operating winding 14 of signal 6, front contact 33 of track relay 6TR, front contact 34 of track relay 5TR, and back point of contact 35 of relay 5HDP to terminal C; and relay 6LR is energized over a line circuit which passes from terminal B, 30 at signal 5, through the back point of contact 32 of relay 5HDP, relay 6LR, front contact 36 of track relay 6TR, back point of contact 37 of relay 5LR, and back point of contact 35 of relay 5HDP. Lamp 6LE, therefore, is energized over front contact 38 of relay 6LR so that, with upper unit U of signal 6 energized in the reverse direction, signal 6 displays a yellow light over a white light.

When signal 6 is in this condition, the relay 6HDP is energized by a circuit which passes from terminal B through caution and stop contact 45 15-19 of signal 6, caution contact 17-18 of signal 6, front contact 39 of relay 6LR, and relay 6HDP to terminal C.

When both relay 6HDP and relay 6LR are energized, operating winding 14 of the upper unit of signal 7 is energized in the normal direction over a line circuit which passes from terminal B at signal 6 through front point of contact 40 of relay 6HDP, front contact 41 of relay 6TR, front contact 42 of relay 7TR, operating winding 14 of signal 7, and front point of contact 43 of relay 6HDP to terminal C. Signal 7, therefore, displays a single green light.

When signal 7 is in this condition, relay 7HDP is energized over a circuit which includes clear contact 15-16 of signal 7 and relay 7HDP is energized over a circuit which includes front contact 44 of relay 7DP.

When relay 7HDP is energized and relay 7LR is deenergized, operating winding 14 of the upper unit of signal 8 is energized in the normal direction over a line circuit which passes from terminal B at signal 7, through front point of contact 45 of relay 7HDP, front contact 46 of relay 7TR, front contact 47 of relay 8TR, operating winding 14 of signal 8, and front point of contact 48 of relay 7HDP to terminal C; and relay 8LR is energized over a line circuit which passes from terminal B at signal 7, through front point of contact 45 of relay 7HDP, back point of contact

49 of relay 7LR, front contact 50 of track relay 8TR, relay 8LR, and front point of contact 48 of relay 7HDP to terminal C. Lamp 8LE, therefore, is energized over front contact 51 of relay 8LR so that with the upper unit energized in the normal direction, signal 8 displays a green light over a white light to indicate "proceed at normal speed."

When signal 8 displays the proceed at normal speed indication, the relay 8DP is energized over clear contact 15-16 of signal 8 so that relay 8HDP is energized over front contact 52 of relay 8DP.

Under this condition, that is, with both relay 8HDP and relay 8LR energized, the line circuit for the control of the upper unit for the signal next in rear (not shown) is supplied with energy of normal polarity over the front points of contacts 52 and 53 of relay 8HDP, and the signal control relay (not shown) for such rear signal is energized over a circuit which includes front contact 54 of relay 8DP and front point of contact 55 of relay 8LR as well as front point of contact 53 of relay 8HDP. The signal (not shown) next in rear, therefore, also displays a green light over a white light which is the normal proceed indication.

Referring next to Fig. 2, it will be noted that section 2T (the section next in advance of section 3T) is shown together with the usual signal and associated apparatus. Signals 2 and 4 function in all respects in a manner similar to that described for the signals shown in Figs. 1A and 1B. The control for signal 3, however, has been modified somewhat. That is, as will be explained more in detail hereinafter, signal 3 displays the stop indication whenever section 2T is occupied as well as when section 3T is occupied; and, when section 2T is occupied, signal 3 can be caused to display a less restrictive indication only if a following train consumes a predetermined amount of time in section 4T. This arrangement provides for safer train operation particularly on down grades, in that a following train is required to stop at the second signal in rear of an occupied block if and only if such train exceeds the authorized speed in approaching such second signal. At the same time, this arrangement permits the following train to pass the signal without stopping if the speed of the train is properly controlled.

Furthermore, when section 2T is occupied, the first restrictive proceed indication will be displayed at signal 7 so that five clear sections are provided between signal 7 and the occupied section instead of four clear sections, as shown for the system shown in Figs. 1A and 1B. Additional braking distance, therefore, is provided so that heavy tonnage trains which may be unable to stop at signal 3 will be certain to stop before passing signal 2.

The reference character 2TE designates a normally deenergized timing device, here shown as a relay having a slow pickup characteristic.

The track battery 13 supplies energy to the rails of section 3T over either a front contact 60 of the track relay 2TR or a front contact 61 of the timing relay 2TE. That is, when track relay 2TR becomes deenergized, track relay 3TR will also become deenergized so that signal 3 will indicate "stop", and when relay 2TR is deenergized, relay 3TR can be energized to cause signal 3 to display a restrictive proceed indication only if the timing relay 2TE has completed its operation.

The reference character 3AR designates a normally energized approach relay which is connected in series with the line circuits for section 4T and which is effective to initiate operation of the timing relay 2TE when section 4T becomes occupied. While relay 3AR, as here shown, will become deenergized only when section 4T is occupied, the control for relay 3AR, if desired, may be modified to include one or more sections to the rear of section 4T.

With the train K occupying section 2T so that both track relays 2TR and 3TR are deenergized and both signals 2 and 3 are displaying the stop indication, I shall assume that a following train 15 enters section 4T so that track relay 4TR becomes released.

When track relay 4TR is released, approach relay 3AR will become deenergized, this relay having been previously energized over a circuit 20 which passes from terminal B through relay 3AR, back point of contact 62 of relay 3HDP, relay 4LR, front contact 63 of track relay 4TR, back point of contact 64 of relay 3LR, and back point of contact 65 of relay 3HDP to terminal C.

When relay 3AR is deenergized, the operation of timing relay 2TE will be initiated by a circuit which passes from terminal B through back point of contact 66 of relay 2HDP, back contact 67 of track relay 2TR, relay 2TE, back contact 68 of approach relay 3AR, back point of contact 69 of track relay 3TR, back point of contact 70 of relay 2LR, and back point of contact 71 of relay 2HDP to terminal C.

As soon as timing relay 2TE completes its operation so that its front contact 61 becomes closed, track relay 3TR will become energized so that signal control relay 3LR will become energized to cause signal 3 to display a proceed indication. The circuit for relay 3LR may be traced 35 from terminal B at signal 2, through back point of contact 66 of relay 2HDP, relay 3LR, front point of contact 69 of relay 3TR (which is now closed), back point of contact 70 of relay 2LR, and back 40 point of contact 71 of relay 2HDP to terminal C.

The previously traced energizing circuit for timing relay 2TE will become opened when relay 3TR becomes energized. The relay 2TE, however, is provided with a holding circuit which 50 passes from terminal B through back point of contact 66 of relay 2HDP, back contact 67 of relay 2TR, relay 2TE, front contact 72 of relay 2TE, and back point of contact 71 of relay 2HDP to terminal C. The holding circuit will maintain 55 timing relay 2TE in its operated condition until such time as section 2T becomes unoccupied, whereupon the timing relay will return to its initial deenergized condition ready for the next operation.

It will be apparent that the following train 60 will receive a restrictive proceed indication or a stop indication at signal 3 according as such train consumes more or less time, respectively, than the operating time of relay 2TE.

While the arrangement shown in Fig. 2 is illustrated and described as being applied to the first signal in rear of a signal displaying the stop indication, it is understood that a similar arrangement might be provided for any of the 70 signals displaying other than the normal proceed indication. For example, the signal control relay 6LR for signal 6 might be controlled by a timing device, in such a manner that signal 6 would display the same indication as signal 5, 75 when section 5T is occupied, and would display

its usual less restrictive indication only if a train consumed a predetermined amount of time in section 7T.

The modification shown in Fig. 3, illustrates a 5 flashing device designated by the reference character FR and here shown as the usual and well-known flasher relay. The relay FR is controlled by a front contact 74 of the signal control relay LR so that the flasher relay FR is energized whenever the relay LR is energized. The lower 10 unit lamp LE is in turn controlled by front contact 74 of relay LR and by contact 75 of flasher relay FR so that the indication provided by that unit is a flashing light instead of a steady light. The modification shown in Fig. 3 may be applied to each lower unit of any or all of the 15 signals shown if it is desired to provide a more distinctive indication.

From the foregoing description of the apparatus embodying my invention, it is apparent 20 that I have provided simple and reliable apparatus for controlling a six-indication, five-block system of signaling wherein only direct current is utilized and wherein only three line control wires are required. Furthermore, my system may be modified to provide restrictive indications 25 which may be changed to less restrictive indications if the speed of the trains is controlled properly, or the system may be modified to provide more arresting indications by flashing the 30 lamps providing such indications.

Although I have herein shown and described 35 only several forms of apparatus embodying my invention, it is understood that various changes and modifications may be made therein within the scope of the appended claims without departing from the spirit and scope of my invention.

Having thus described my invention, what I claim is:

1. A railway signal system comprising; a first, a second, a third, a fourth, a fifth, and a sixth track section over which traffic normally progresses in the order named; a polarized line circuit for each section, a relay for each section, means controlled by a train occupying the sixth section effective to deenergize both the line circuit and the relay of that section, means then effective to deenergize the line circuit for the fifth section and to energize the relay for that section, means then effective to energize the line circuit for the fourth section in the reverse direction and to deenergize the relay for that section, means then effective to energize the line circuit for the third section in the reverse direction and to energize the relay for that section, means then effective to energize the line circuit for the second section in the normal direction and to deenergize the relay for that section, means then effective to energize the line circuit for the first section in the normal direction and to energize the relay for that section, and signaling means controlled by the last mentioned line circuit and relay.

2. A railway signal system comprising; a first, a second, a third, a fourth, a fifth, and a sixth track section over which traffic normally progresses in the order named; a polarized line circuit for each section, a relay for each section, means controlled by a train occupying the sixth section effective to deenergize both the line circuit and the relay of that section, means then effective to deenergize the line circuit for the fifth section and to energize the relay for that section, means then effective to energize the line circuit for the 70 first section in the normal direction and to energize the relay for that section, and signaling means controlled by the last mentioned line circuit and relay.

- line circuit for the fourth section in the reverse direction and to deenergize the relay for that section, means then effective to energize the line circuit for the third section in the reverse direction and to energize the relay for that section, means then effective to energize the line circuit for the second section in the normal direction and to deenergize the relay for that section, means then effective to energize the line circuit for the first section in the normal direction and to energize the relay for that section, a signal for the sixth section caused to display the stop indication when the associated line circuit and relay are both deenergized, and signals one for each of the remaining sections and each caused to display a distinctive proceed indication in accordance with the condition of the associated line circuit and relay. 5
20. 3. A railway signal system comprising; a first, a second, a third, a fourth, and a fifth track section over which traffic normally progresses in the reverse direction to the order named; a polarized line circuit for each section, a relay for each section, means controlled by a train occupying the first section and effective to deenergize both the line circuit and the relay for that section, means then effective to deenergize the line circuit for the second section and 10 to energize the relay for that section, means then effective to energize the line circuit for the third section in the reverse direction and the deenergize the relay for that section, means then effective to energize the line circuit for 15 the second section in the reverse direction and to energize the relay for that section, means then effective to energize the line circuit for the first section in the normal direction and to deenergize the relay for that section, and a signal for the fifth section controlled by the line circuit and relay for that section and caused to indicate that the first section is occupied. 20
4. A railway signal system comprising; a first, a second, a third, a fourth, and a fifth track section over which traffic normally progresses in the reverse direction to the order named; a polarized line circuit for each section, a relay for each section, means controlled by a train occupying the first section and effective to deenergize both the line circuit and the relay for that section, means then effective to deenergize the line circuit for the second section and to energize the relay for that section, means then effective to energize the line circuit for the third section in the reverse direction and to deenergize the relay for that section, means then effective to energize the line circuit for the second section in the reverse direction and to energize the relay for that section, means then effective to energize the line circuit for the first section in the normal direction and to deenergize the relay for that section, a signal for the first section caused to display the stop indication when the associated line circuit and relay are both deenergized, and signals one for each of the remaining sections and controlled by the associated line circuits and relays, said remaining signals each being caused to display a distinctive and a successively less restrictive indication in accordance with their numerical order. 25
5. In combination, two adjacent sections of railway track each having a track circuit including a track relay, a line circuit for the rear section including a front contact of each of
- said track relays, another line circuit for the rear section including a front contact of the track relay for that section, a signal for the forward section, a pole changing relay controlled by said signal for governing said first line circuit, means including another relay governed by said signal for controlling said second line circuit, a line relay connected to said second line circuit, and a signal for the rear section controlled jointly by said line relay and by said first line circuit. 30
6. In combination, a plurality of successive sections of railway track, each such section having a track circuit including a track relay, a plurality of signals one for each section and each such signal comprising a first unit and an auxiliary unit, means for controlling each first unit in accordance with traffic conditions in advance of the associated signal, a contact for each section which is closed only when the first unit of the associated signal is displaying its least restrictive indication, a signal control relay for each section for controlling the auxiliary unit of the associated signal, and two circuits for each signal control relay, each circuit including a front contact of the track relay for the associated section, one circuit including a back contact of the signal control relay for the section next in advance and the other circuit including a front contact of the signal control relay for the section next in advance as well as said contact for said advance section. 35
7. In combination, a forward section and a rear section of railway track, a signal for each section and each signal comprising two units, a relay for controlling one unit of the signal for the forward section, said relay being energized under certain traffic conditions in advance of said signal and being deenergized under other traffic conditions in advance of said signal, another relay for controlling one unit of the signal for the rear section, one circuit for energizing said other relay including a back contact of said first relay, and another circuit for energizing said other relay including a front contact of said first relay. 40
8. In combination with a stretch of railway track comprising a plurality of track sections, a source of current and a track relay for each section, a signal for each section comprising a first and a second indication unit, a signal control relay for each section for governing the indication displayed by the second unit of its associated signal, means associated with each of said sections and including the associated track relay for governing the indication displayed by the first unit of its associated signal, contacts operably governed by the first unit of each signal, and means for controlling each signal control relay governed by the contacts of the signal for the section next in advance as well as by said signal control relay for said advance section. 45
9. In combination with a stretch of railway track comprising a plurality of track sections, a source of current and a track relay for each section, a signal for each section comprising a first and a second indication unit, a signal control relay for each section for governing the indication displayed by the second unit of its associated signal, means associated with each of said sections and including the associated track relay for governing the indication displayed by the first unit of its associated signal, a pole changing relay governed by the first unit of each signal and by the associated signal control relay, and means for controlling each signal control relay governed 50
- 70
- 75

by the pole changing relay of the signal for the section next in advance as well as by said signal control relay for said advance section.

10. In combination, a stretch of railway track divided into a plurality of track sections each having a track circuit including a track relay, said plurality of sections including an occupied section and five successive sections to the rear of such occupied section, a signal for each section and each such signal comprising a first unit capable of displaying several distinctive indications and a second unit capable of displaying one indication or no indication, and means governed by said track relays and including three line wires for each section for controlling the two units of each signal in such a manner that one indication is displayed by the first unit of the signal for said occupied section as well as by the first unit of the section first in rear, another indication is displayed by the first units of the signals for the second and third sections in rear, a different indication is displayed by the first units of the signals for the fourth and fifth sections in rear, and an indication is displayed by the second unit of the signal for the section first in rear of the occupied section as well as by the second units of the signals for the third and fourth sections in rear.

11. A railway signal system comprising a stretch of railway track divided into a plurality of track sections, a plurality of signals one for each section and each such signal comprising a searchlight signal mechanism and an auxiliary lamp, means for governing each signal in such manner that when a particular section is occupied by a train the mechanism of the signal for the occupied section and the mechanism of the signal for the first section to the rear of such occupied section are both deenergized, the mechanisms of the signals for the second and third sections to the rear are supplied with current of reverse polarity, the mechanisms of the signals for the fourth and fifth sections to the rear are supplied with current of normal polarity, and the lamps of the signals for the first and third as well as the fifth sections to the rear of the occupied section are energized.

12. In combination, three successive sections of railway track including a forward section and a rear section as well as an intermediate section, a track circuit including a track relay for both the forward section and the rear section, a track relay connected across the rails of the intermediate section, a source of current, means including a front contact of the track relay for the forward section for connecting said source of current to the rails of the intermediate section, a timing device, means controlled by the track relays of each section for initiating the operation of said timing device when the forward section and the rear section both become occupied, a circuit for connecting said source of current to the rails of the intermediate section when said device completes its operation, and a signal for the intermediate section governed by the track relay for that section.

13. In combination, a forward section and a rear section of railway track, a track relay for each section connected across the rails of that section, a source of current connected across the rails of the forward section, another source of current connected across the rails of the rear section through a front contact of the track relay for the forward section, a signal for each section controlled by the track relay for that section, a

slow acting device, means for initiating the operation of said device when a train is approaching the signal for the rear section provided the forward section is then occupied by another train, and means for connecting said other source of current to the rails of the rear section when said device completes its operation.

14. In combination, a forward section and a rear section of railway track, a track relay for each section connected across the rails of that section, a source of current connected across the rails of the forward section, another source of current connected across the rails of the rear section through a front contact of the track relay for the forward section, a signal for each section controlled by the track relay for that section, a normally deenergized slow acting relay, a circuit including a back contact of both track relays for energizing said relay when a train is approaching the signal for the rear section, a circuit including a front contact of said slow acting relay and a back contact of the track relay for the forward section for holding said relay in its energized condition, and means including a front contact of said slow acting relay for connecting said other source with the rails of the rear section.

15. In combination, three successive sections of railway track including a forward section and a rear section as well as an intermediate section, a track circuit including a track relay for both the forward section and the rear section, a track relay connected across the rails of the intermediate section, a source of current, means including a front contact of the track relay for the forward section for connecting said source of current to the rails of the intermediate section, a timing device, means controlled by the track relays of each section for initiating the operation of said timing device when the forward section and the rear section both become occupied, means for supplying energy to the rails of the intermediate section when said device completes its operation, and a signal for the intermediate section comprising a first unit controlled by the track relays for the intermediate section and the forward section and a second unit controlled by the track relay for the intermediate section.

16. In combination, three successive sections of railway track including a forward section and a rear section as well as an intermediate section, a track circuit including a track relay for both the forward section and the rear section, a track relay connected across the rails of the intermediate section, a source of current, means including a front contact of the track relay for the forward section for connecting said source of current to the rails of the intermediate section, a timing device, means controlled by the track relays of each section for initiating the operation of said timing device when the forward section and the rear section both become occupied, means for supplying energy to the rails of the intermediate section when said device completes its operation, and a signal for the intermediate section comprising a mechanism and a lamp, said mechanism controlled by the track relays for the intermediate section and the forward section and said lamp controlled by the track relay for the intermediate section.

17. In combination, three successive sections of railway track including a forward section and a rear section as well as an intermediate section, a track circuit including a track relay for both the forward section and the rear section, a track

relay connected across the rails of the intermediate section, a source of current, means including a front contact of the track relay for the forward section for connecting said source of current to the rails of the intermediate section, a timing device, means controlled by the track relays of each section for initiating the operation of said timing device when the forward section and the rear section both become occupied, means for supplying energy to the rails of the intermediate section when said device completes its operation, and a signal for the intermediate section comprising a first unit and a second unit, said two units controlled by the track relays for the intermediate section and the forward section in such a manner that said signal is caused to indicate a more restrictive or a less restrictive indication according as the track relay for the intermediate section is deenergized or energized respectively.

18. In combination, a stretch of railway track divided into a plurality of sections, a signal for one of said sections comprising two units, one unit being a mechanism capable of displaying three different indications and the other unit being a lamp which in conjunction with particular indication of the first unit causes the display of a less restrictive or a more restrictive indication according as said lamp is lighted or extinguished respectively, means for causing said other unit to become extinguished when a particular section in advance of said signal is occupied, a timing device, means for initiating the operation of said timing device when another

train occupies a particular section in rear of said signal if said advance section is also occupied, and means effective to light said lamp when said timing device completes its operation.

19. In combination, a stretch of railway track divided into a plurality of sections, a signal for one of said sections comprising two units, one unit being a mechanism capable of displaying three different indications and the other unit being a lamp which in conjunction with a particular indication of the first unit causes the display of a less restrictive or a more restrictive indication according as said lamp is lighted or extinguished respectively, means for controlling said mechanism in accordance with traffic conditions in certain sections in advance of said signal, a line relay controlled by traffic conditions in such advance section, a flasher relay controlled by said line relay, and a circuit for said lamp controlled by said line relay and including contacts of said flasher relay.

20. In combination, a section of railway track, a signal for said section comprising two units, one unit being a mechanism responsive to the polarity of the current supplied thereto and the other unit being a lamp, a polarized line circuit connected to said mechanism and reversibly governed by traffic conditions in advance of said signal, a flasher relay for controlling said lamp, and means including another line circuit for controlling said flasher relay in accordance with traffic conditions in advance of said signal.

EARL M. ALLEN.
